UNITED STATES PATENT OFFICE.

HIRAM D. CURRIER, OF CHICAGO, ILLINOIS, ASSIGNOR TO KELLOGG SWITCHBOARD & SUPPLY COMPANY, OF CHICAGO, ILLINOIS, A CORPORATION OF ILLINOIS.

TRUNK-CIRCUIT.

1,306,406.

Specification of Letters Patent. Patented June 10, 1919.

Application filed April 5, 1915. Serial No. 19,168.

To all whom it may concern:

Be it known that I, HIRAM D. CURRIER, a citizen of the United States of America, residing in Chicago, county of Cook, and State 5 of Illinois, have invented certain new and useful Improvements in Trunk-Circuits, of which the following is a specification.

My invention relates to telephone systems and has more particularly to do with systems 10 employing two-way trunk circuits for use between two exchanges as between a main and private branch exchange, and has for its object, a novel and improved system of the above type.

15 In systems of the above character a call originating at the main exchange will be answered by a so-called A-operator, who upon finding that the wanted line terminates at a different operator's position, as at a 20 private branch exchange operator's position, extends the connection over a trunk line leading to the second exchange. The operator then presses a ringing key to operate the signaling device associated with the opposite end of the trunk circuit, that is, terminating at the private branch exchange. In such systems should the operator at the 25 private branch exchange connect with the trunk circuit while the operator at the main exchange is actuating the ringing key, ringing current will be transmitted through the operator's set at the private branch exchange, thus producing undesirable clicks in the receiver of the operator's set. One of 30 the objects of my invention is the provision of means for preventing the operative connection of the P. B. X. operator's link circuit with the trunk circuit while the operator at the main exchange is applying ringing current to the trunk circuit. Other objects 35 of my invention will be more particularly pointed out in the appended claims.

For a more complete understanding of my invention reference may be had to the accompanying drawing in which only sufficient apparatus is shown for connecting a calling subscriber at a main exchange with a called subscriber at a sub-exchange or at a private branch exchange. The connection as shown 40 is completed through the medium of the calling subscriber's line equipment L, link circuit C, trunk circuit D, private branch exchange link circuit E and the line equipment L¹ of the called subscriber's line.

Referring now more in detail to the apparatus illustrated, the substation A may be of any well-known or suitable type of common battery substation. The line circuit L comprises the line relay LR, line lamp S, cut-off relay CO and multiple jacks J. 55 The substation B is similar to the substation A in all respects. The line circuit L¹ is similar to the line circuit L except that only one jack is shown connected to the line of the called subscriber.

60 The cord circuit C may be of any well-known type and as shown, comprises an answering plug AP and a calling plug CP connected by the heavily marked conductors and having the condensers K and K¹ interposed. Associated with the answering plug AP is the answering tip supervisory relay AT and the answering sleeve supervisory relay AS, the two supervisory relays controlling the circuit of the answering supervisory lamp AL. Associated with the calling plug CP is the calling tip supervisory relay CT and the calling sleeve supervisory relay CS, the two relays controlling the circuit of the calling supervisory lamp CL. At 65 O is shown an operator's set adapted to be connected to the cord circuit through the medium of the operator's listening key LK. The link circuit C is adapted to complete connections between local substations or for 70 extending a call from a local substation over the trunk circuit D to a subscriber at a private branch exchange or for completing a call initiated at private branch exchange and extended to the main exchange 75 over the trunk circuit D.

75 The trunk circuit D terminates in the jack J² at the operator's position in the main exchange and in the jack J³ at the operator's board at the private branch exchange. Associated with the jack J² is a line relay LR², line signal S², and cut-off relay CO². The line relay LR² and line signal S² are for use when connections are extended from the private branch exchange to the main exchange. Associated with the jack J³ is a double wound link control relay LC, alternating current relay AC and the line signal S³. These relays come into operation when 80 connections are extended from the main exchange to the private branch exchange.

85 The private branch exchange operator's link circuit E comprises an answering plug

AP¹ and a calling plug CP¹ connected through the medium of the heavily marked conductors and having condensers K² and K³ interposed therein. The answering tip 5 supervisory relay AT¹ and the answering sleeve supervisory relay AS¹, are associated with the answering end of the cord circuit E, and control the circuit of the answering supervisory lamp AL¹ in a well-known manner. Associated with the called end of the 10 cord circuit is a calling tip supervisory relay CT¹ and a calling sleeve supervisory relay CS¹, for controlling the operation of the calling supervisory lamp CL¹. The operator's set O¹ is adapted to be connected to the 15 link circuit E through the medium of the listening key LK¹.

Having described in general the apparatus employed in the preferred embodiment 20 of my invention as herein illustrated, a connection from a calling to a called subscriber will now be described in detail.

Assuming now that the subscriber at sub- 25 station A desired to initiate a call, upon re- moving his receiver from the switch-hook, a circuit is closed through the line relay LR. The line relay LR, upon energizing, closes a circuit through the line lamp S. The operator upon noting the glowing of the line 30 lamp S inserts the answering plug AP of the link circuit C into the jack J of the line circuit L thus closing a circuit through the answering sleeve supervisory relay AS and cut-off relay CO. This circuit extends from 35 battery through the winding of the said answering sleeve supervisory relay AS, sleeve conductor of the plug AP and jack J and winding of cut-off relay CO to ground. The cut-off relay CO, upon energizing, dis- 40 connects the line relay LR from the subscriber's line and completes connection be- 45 tween the conductors of the jack J and the subscriber's line thus closing a circuit through the answering tip supervisory relay 50 AT. The circuit for the answering tip supervisory relay AT extends from battery through the winding of said relay AS, sleeve conductor of plug AP and jack J, alternate contact 3 of cut-off relay CO, to 55 and through the substation A, alternate contact 2 of relay CO, tip conductor of jack J and plug AP and through the winding of answering tip supervisory relay AT to ground. Relay AT, upon energizing, pre- 60 vents the premature glowing of the answering supervisory lamp AL by opening its contact 4. The operator now actuates the listening key LK to connect her set O with the link circuit C and inquires the wants of 65 the calling subscriber. Upon learning that the calling subscriber desires connection with a subscriber at the private branch exchange, the operator makes a preliminary busy test and then inserts the calling plug 70 CP into jack J² of the trunk circuit D.

Upon the insertion of the calling plug CP into jack J², an energizing circuit is closed through cut-off relay CO² associated with jack J². This circuit extends from battery 75 through the calling sleeve supervisory relay CS, sleeve conductor or plug CP and jack J² and the winding of cut-off relay CO² to ground. The cut-off relay CO², upon energizing, disconnects the line relay LR² from the strands of the trunk circuit D and connects the tip and sleeve conductors of the jack J² to the heavily marked conductors of the trunk circuit D. The operator now actuates the ringing key RK to connect 80 ringing current from the generator G to the trunk circuit D. The path for the ringing current extends from the ungrounded pole of generator G through alternate contacts of the ringing key RK, tip conductor of calling plug CP and jack J², alternate contact 6 of cut-off relay CO², over the trunk conductor 36 to the private branch exchange 85 then through the condenser K³, lower winding of the link control relay LC, winding of alternating current relay AC back over the opposite trunk conductor 37, through alternate contact 7 of cut-off relay CO², sleeve conductor of the jack J² and plug CP and through the alternate contact of ringing key RK to battery, back to the grounded pole 90 of generator G. The link control relay LC, upon energizing, disconnects the tip and sleeve conductors of the jack J³ from the trunk conductors by opening its normal contacts 9 and 10, and closes a locking circuit 95 for itself at its alternate contact 11 independent of its original energizing circuit. The locking circuit for link control relay LC extends from battery through the upper winding of said relay, its alternate contact 100 105 11, contact 12 of jack J³ to ground. A further result due to the energizing of link control relay LC is the closing of a circuit through the line lamp S³, traced from battery through the said lamp S³, alternate contact 11 of link control relay LC, normal contact 12 of jack J³ to ground. 110

The operator at the private branch exchange upon noting the glowing of the line lamp S³ inserts the answering plug AP¹ of 115 the link circuit E into the jack J³ of the trunk circuit D. Upon the insertion of the answering plug AP¹ into jack J³, the circuit of the link control relay LC is opened at normal contact 12 of jack J³. However, if ring- 120 ing current is being applied to the trunk conductors of the trunk circuit D, the alternating current relay AC will remain energized, as long as current is being applied to the trunk circuit over the hereinbefore 125 traced circuit, and operates to prevent the link control relay LC from deenergizing and connecting trunk conductors to the tip and sleeve conductors of the answering plug AP¹. The circuit for preventing the de- 130

- energization of the link control relay LC while ringing current is being applied to the trunk conductors, extends from battery through the upper winding of said relay 5 LC, alternate contact 11 of said relay and alternate contact 13 of alternating current relay AC to ground. As soon, however, as the link control relay LC deenergizes, a circuit is established for answering sleeve supervisory relay AS¹ and answering tip supervisory relay AT¹ of link circuit E. The circuit for answering sleeve supervisory relay AS¹ extends from battery through the winding of said relay AS¹ sleeve conductor of plug AP¹ and jack J³, normal contact 9 of relay LC, alternate contact 6 of relay CO², tip conductor of jack J² and plug CP, alternate contact 14 of relay CS and through the calling tip supervisory relay CT to ground. The circuit for the answering tip supervisory relay AT¹ extends from battery at link circuit C through the winding of calling sleeve supervisory relay CS, through the sleeve conductor of plug CP and jack J², alternate contact 7 of cut-off relay CO², normal contact 10 of relay LC, tip conductor of the jack J³ and plug AP¹ and through the winding of said answering tip supervisory relay AT¹ to ground. The energizing 10 of the answering tip supervisory relay AT¹ prevents a premature glowing of answering supervisory relay AL¹ while the energization of tip supervisory relay CT of link circuit C opens the circuit of the calling supervisory lamp CL and indicates to the operator at link circuit C that the operator at the private branch exchange has inserted the answering plug AP¹ into the jack J³ of the trunk circuit D. The operator at link 15 circuit E now operates listening key LK¹ to bridge her set O¹ across the strands of the link circuit E.
- The operator at the link circuit C or the subscriber at calling substation A, as the case 20 may be, now informs the operator of the link circuit E what local substation of the private branch exchange is desired. The operator at the private branch exchange upon learning the number of the desired 25 substation, makes a preliminary busy test, and assuming that the called line is idle, inserts the calling plug CP¹ into the jack J¹ of the called line. Upon the insertion of the calling plug CP¹ into jack J¹ an energizing 30 circuit is closed for the cut-off relay CO¹ of the called line, traced from battery through the winding of the calling sleeve supervisory relay CS¹, sleeve conductor of the plug CP¹ and jack J¹ and through the 35 winding of cut-off relay CO¹ to ground. The calling sleeve supervisory relay CS¹, upon energizing, closes a circuit through the calling supervisory lamp CL¹ at its contact 17. Cut-off relay CO¹ upon energizing, 40 connects the line relay LR¹ from the line

of the called subscriber and connects the lines of the called subscriber to the strands of the cord circuit D through alternate contacts 18, 19. The operator now operates the ringing key RK¹ to connect ringing current from generator G¹ to the line of the called substation. The circuit for the ringing current extends from the ungrounded pole of generator G¹ through alternate contact of ringing key RK¹, tip conductor of calling plug CP¹ and jack J¹, alternate contact 19 of relay CO¹ to and through the substation B, alternate contact 18 of relay CO¹, sleeve conductor of jack J¹, and plug CP¹ and alternate contact of ringing key RK¹ to battery, and through battery back to the grounded terminal of generator G¹. The called subscriber now responds by removing his receiver from the switch-hook and thereby closes a circuit through the calling tip supervisory relay CT¹. This circuit extends from battery through the calling sleeve supervisory relay CS¹, sleeve conductor of the calling plug CP¹ and jack J¹, alternate contact 18 of relay CO¹, to and through substation B, alternate contact 19 of relay CO¹, tip conductor of jack J¹ and calling plug CP¹ and through the winding of the calling tip supervisory relay CT¹ to ground. The calling tip supervisory relay AT¹, upon energizing, opens the circuit of the calling supervisory lamp CL¹ at its contact 20, thus indicating to the operator that the called subscriber has responded. The subscribers may now carry on conversation over 100 the heavily marked conductors.

Assuming that conversation is now terminated the calling subscriber, upon replacing his receiver, opens the circuit of the answering tip supervisory relay AT of link circuit 105 C and thereby allows the same to deenergize. The answering tip supervisory relay AT, upon deenergizing, closes a circuit for answering supervisory lamp AL at its contact 4. The called subscriber upon replacing 110 his receiver opens the circuit of the calling tip supervisory relay CT¹ of link circuit E, at switch-hook contacts of the substation thereby allowing relay CT¹ to deenergize. The calling tip supervisory relay CT¹, upon 115 deenergizing, closes a circuit through the calling supervisory lamp CL¹, thus indicating to the operator at link circuit E that the called subscriber has replaced his receiver. The operator at link circuit E now 120 removes the calling plug CP¹ and answering plug AP¹ from their respective jacks. The removal of the calling plug CP¹ allows the cut-off relay CO¹ of line circuit L¹ and calling supervisory relay CS¹ to deenergize and 125 return to normal. The removal of the answering plug AP¹ from jack J³ of trunk circuit D allows the answering tip supervisory relay AT¹ and answering sleeve supervisory relay AS¹ of link circuit E and calling tip 130

supervisory relay CT of link circuit C to deenergize and return to normal. The calling tip supervisory relay CT, upon deenergizing, closes the circuit of calling supervisory lamp CL of link circuit C at its normal contact 23. The operator at link circuit C upon noting the glowing of the answering supervisory lamp AL and calling supervisory lamp CL removes the answering plug AP and the calling plug CP from their respective jacks. The removal of answering plug AP from jack J allows the answering supervisory relay AS and cut-off relay CO to return to normal and the removal of the calling plug CP from jack J² of the trunk circuit D, allows the cut-off relay CO² of trunk circuit D to return to normal.

Assuming now that a subscriber at the private branch exchange wishes to communicate with a subscriber at the main exchange, the subscriber at private branch exchange upon removing his receiver, causes the line signal S¹ to glow in the same manner as described for the line signal S associated with the line circuit L of substation A. The operator at the private branch exchange now inserts the answering plug AP¹ into the jack J¹ of the calling subscriber, operating the cut-off relay CO¹ of the line circuit L¹ and answering sleeve supervisory relay AS¹ of link circuit E in a well-known manner. The operator now actuates listening key LK¹ to learn the wants of the calling subscriber. Upon learning that the wanted subscriber is one whose line terminates at the main exchange, she inserts the calling plug CP¹ into jack J³ of the trunk circuit D. Upon the insertion of the plug CP¹ into the jack J³, a circuit is closed through line relay LR² associated with jack J², traced from battery through the winding of said relay, normal contact 7 of relay CO², normal contact 10 of relay LC, tip conductor of jack J³ and plug CP¹ and through the calling tip supervisory relay CT¹ to ground. Line relay LR², upon energizing, causes line lamp S² to glow. The operator at the main exchange upon noting the glowing of the line lamp S², inserts the answering plug AP of link circuit C into jack J² of trunk circuit D. The insertion of plug AP into jack J² closes a circuit through the cut-off relay CO² of the trunk circuit D and the answering sleeve supervisory relay AS of link circuit C in series. This circuit extends from battery through winding of said answering supervisory relay AS, sleeve conductor of plug AP and jack J² and through cut-off relay CO² to ground. The cut-off relay CO², upon energizing, disconnects line relay LR² from the trunk circuit D and connects the conductors of jack J² with the strands of the trunk circuit thus closing a series circuit through the calling tip supervisory relay CT¹ of link circuit E and answering supervisory relay AS of link circuit C and also closing a series

circuit through the calling sleeve supervisory relay CS¹, the link circuit E and answering tip supervisory relay AT of the link circuit C. The former circuit extends from battery through the winding of answering sleeve supervisory relay AS, sleeve conductors of answering plug AP and jack J², alternate contact 7 of relay CO², normal contact 10 of relay LC, tip conductor of jack J³ and plug CP¹ and through the winding of the calling tip supervisory relay CT¹ of link circuit E to ground. The latter circuit extends from battery through the calling sleeve supervisory relay CS¹ of link circuit E, sleeve conductor of plug CP¹ and jack J³, normal contact 9 of relay LC, alternate contact 6 of relay CO², tip conductor of jack J² and plug AP and the winding of the answering tip supervisory relay AT of link circuit C to ground. The operator at the link circuit C is now informed of the calling subscriber's desires and completes the connection to the line of the wanted subscriber by inserting the calling plug CP of the link circuit C into the jack J of the wanted subscriber. The subscribers may now carry on conversation over the heavily marked conductors. The calling subscriber upon replacing his receiver causes the answering supervisory lamp AL¹ to glow thus notifying the operator at the private branch exchange that disconnection is desired. The operator then removes the answering plug AP¹ and the calling plug CP¹ of the link circuit E from their respective jacks. The removal of the calling plug CP¹ from jack J³ of trunk circuit D causes the answering tip supervisory relay AT of link circuit C to deenergize and close the circuit of the answering supervisory lamp AL. The operator at the main exchange now removes the answering plug AP and the calling plug CP from their respective jacks allowing the apparatus to return to normal. Had the calling subscriber wanted connection with a local private branch exchange subscriber, the operator at the private branch exchange would have taken the calling plug CP¹ of link circuit E and inserted it into the jack of the wanted subscriber and operated the ringing key RK¹ to signal the wanted subscriber. The operation of the apparatus in establishing this connection is practically the same as hereinbefore described.

While I have illustrated the preferred embodiment of my invention in certain specific circuit arrangements, yet, it is to be understood that I do not wish to be limited to the specific arrangements shown as many changes and modifications will readily suggest themselves to one skilled in the art, and therefore I desire to cover all changes and modifications that come within the contemplated spirit and scope of the appended claims.

Having described my invention, what I

claim as new and desire to secure by United States Letters Patent, is

1. In a telephone system a trunk circuit provided with a pair of terminals, connecting means adapted to be connected to one of said terminals, means for applying ringing current to the other of said terminals, and means for preventing the operative association of the said connecting means with the 10 said trunk while ringing current is being applied.

2. A telephone system comprising a trunk circuit extending between two operators' boards, a terminal at one of said boards for 15 connection to said trunk, means at the other of said boards for applying ringing current to the said trunk, and means for preventing the operative association of the said terminal with the said trunk while ringing current is 20 being applied thereto.

3. In a telephone system an A-operator's board and a B-operator's board, a trunk circuit extending between said boards, an operator's set associated with said B-operator's board, means at the A-operator's board 25 for applying ringing current to the said trunk circuit, and means included in the said trunk circuit for preventing the connection of said operator's set to the said trunk 30 while ringing current is connected therewith.

4. In a telephone system an A-operator's board and a B-operator's board, an operator's set at said B board, a trunk circuit extending between the said boards, means at 35 the A-operator's board for applying ringing current to said trunk circuit, and means in said trunk circuit for preventing the operative associating of the said operator's set with the said trunk circuit while ringing 40 current is being applied to the said trunk circuit.

5. In a telephone system a trunk line provided with a pair of terminals, connecting means for one end of said trunk circuit, 45 means for applying ringing current associated with the opposite end of said circuit, and means in said trunk circuit for preventing the operative association of the said connecting means with the said trunk while the 50 said ringing means is connected thereto.

6. In a telephone system a two-way trunk circuit provided with a pair of terminals, connecting means associated with each of said terminals, means for preventing the operative association of the connecting means at one end of said trunk while a call is being signaled for from the opposite end thereof, and means for extending a call in either direction over the said trunk circuit.

60 7. In a telephone system a two-way trunk circuit provided with a pair of terminals and extending between an A board and a B board, means for applying ringing current to one terminal of said trunk circuit, and 65 means at the opposite end of said trunk cir-

cuit for preventing the ringing current from being connected to the other terminal of said trunk circuit, said means including a pair of relays responsive to ringing current, one of said relays being provided with a pair of 70 windings.

8. In a telephone system a two-way trunk circuit provided with a pair of terminals and extending between an A board and a B board, means for applying ringing current 75 to one terminal of said trunk circuit, and means at the opposite end of said trunk circuit for preventing the ringing current from being connected to the other terminal of said trunk circuit.

9. In a telephone system a trunk circuit provided with a pair of terminals, connecting means associated with one of said terminals, ringing means associated with the other of said terminals, a relay responsive to 85 ringing current associated with said trunk circuit for controlling the continuity of said trunk circuit, means for connecting the said ringing means to the said trunk circuit, and means including the said relay for preventing 90 the operative association of said first-named connecting means with the trunk circuit while the said ringing means is connected therewith.

10. An inter-office trunk circuit extending 95 between two operators' switchboards, means for disassociating the ends of said trunk circuit, and a signaling battery adapted to be connected to one end of said trunk circuit to affect such disassociation.

100 11. An inter-office trunk circuit extending between two operators' switchboards, a signaling battery associated with one end of said trunk circuit, and means responsive to the connection of said signaling battery to 105 said trunk circuit for disassociating the opposite end of said trunk circuit from said first end.

110 12. A trunk circuit extending between two operators' boards and terminating in connecting terminals upon said boards, means for operatively disconnecting one of said terminals from the other, said means being responsive to signaling current connected with one end of said trunk circuit.

115 13. In a telephone system, the combination of a calling station, a called station, conductors connecting said stations, calling current generating means at the calling station, means to connect said current generating means to said conductors, a telephone set at the called station, means to connect said telephone set to said conductors, and apparatus at the called station preventing the connection of the telephone set to said 120 conductors while the calling current is connected thereto.

125 14. In a telephone system, the combination of a calling station, a called station, conductors for connecting said stations to 130

gether, calling current generating means at the calling station, a signal at the called station whose operation is controlled by the calling current, a telephone set at the called station adapted to be connected to said conductors, means at the called station preventing the connection of said telephone set to said conductors while the calling current is connected to said conductors.

10 15. In a telephone system, the combination of a main exchange central station, a private branch exchange central station, a telephone set at the private branch exchange central station, a trunk circuit for connecting said stations together, means for enabling the main exchange central station operator to signal the private branch exchange central operator, including a source of calling current and means to apply said source to the trunk circuit, mechanism to connect the receiver of the telephone set of the private branch exchange central station operator to the trunk circuit, and means to prevent the connection of said receiver to said trunk circuit during the application of calling current from said source to said trunk.

15 20 25 30 35 40 45 50 55 60

16. In a telephone system, the combination of a calling station, a called station, conductors for connecting said stations together, a source of calling current at the calling station, and means to connect it to said conductors, a telephone set at the called station including a telephone receiver and

means to connect said receiver to said conductors, and apparatus controlled by the calling current to prevent the connection of said receiver to said conductors while the calling current is connected to said conductors.

17. A trunk circuit extending from one exchange to another, a source of signaling current, means for applying said signaling current to one end of said trunk circuit, and means associated with said trunk circuit for preventing said signaling current from traversing the terminal in which the other end of said trunk circuit terminates, said last means being controlled by said signaling current.

18. A telephone system including a trunk circuit, terminals in which said trunk circuit terminates, a source of signaling current, means for associating said source of current with one end of said trunk circuit, and means for preventing said signaling current from passing through the terminal at the other end of said trunk circuit, said last means being controlled by said signaling current.

Signed by me at Chicago, in the county of Cook and State of Illinois, in the presence of two witnesses.
